Des. 212,391
Patented Oct. 8, 1968

212,391

SURFACE ILLUMINATOR HOUSING FOR AN OPTICAL COMPARATOR

Paul Francis Dietz, 7235 Santa Catalina Circle,
Buena Park, Calif. 90620

Filed Jan. 26, 1968, Ser. No. 10,334

Term of patent 7 years

(Cl. D57—1)

FIG. 1.

FIG. 2.

FIG. 1 is a perspective view of a surface illuminator housing for an optical comparator, embodying my new design; and

FIG. 2 is a perspective view as seen from the opposite side thereof.

I claim:

The ornamental design for a surface illuminator housing for an optical comparator, as shown.
